UNITED STATES PATENT OFFICE.

SAMUEL E. TOMPKINS, OF SING SING, NEW YORK.

IMPROVEMENT IN GIG SADDLE-TREES.

Specification forming part of Letters Patent No. 123,209, dated January 30, 1872.

Specification describing a new and Improved Gig Saddle - Tree, invented by SAMUEL E. TOMPKINS, of Sing Sing, in the county of Westchester and State of New York.

The first part of the invention consists of a construction of the frame whereby it is adapted for making a saddle with short jockeys, and, at the same time, preserving bearings of the requisite length and breadth, which I accomplish by shortening the flanges, though making the main portion as long as heretofore or longer and as wide as the flanges, with the exception of the notches or recesses at the ends of said flanges, to allow of sewing the jockeys as far as needed. The second part of the invention consists of projections on the terret-nuts to fit in the notches in the frame to prevent the nuts from turning around in the tree when screwing the terrets in or out. The third part consists of ribs on the outer edges of the flanges to have sufficient thickness along the edges to insure the security of a perfect form in the casting, while the said flanges are made thin enough between the said ribs and the bearings of the frame to allow of punching the nail or rivet holes readily in case they fail of being formed properly by the casting of the plates. The fourth part consists of a shoulder on the front upright on the crown of the plate for supporting the saddle for said saddle to rest on while the continuation of said support extends up in the hole through the saddle for the bolt, which secure it to the tree to hold it against lateral movement, as well as to support said tree a certain distance above the plate, the tree being fastened on either by a screw-bolt and socket-nut—the latter being at the top—or by a bolt with a cone-nut at the bottom fitted into a countersunk hole in the plate for allowing the nut to sink to the surface so as not to injure the animal's back. The fifth part consists of a detachable crupper - loop having a flattened shank or portion, by which it is connected to the tree by one of the bolts used for attaching the check-rein hook and the saddle, and by a square or other angular projection rising up from the top of the tree, and having a screw-threaded portion and a nut screwing down upon said shank, which has a square or other angular hole for said projection, also a hole for the aforesaid bolt; and the loop is so bent up-

ward at its connection with said shank as to make room for the rear end of the "middle leather" to be placed under it, while the shank is firmly clamped to the tree. The sixth part of the invention consists of a cone-shaped projection raised on the upper side of the shank of the check-rein hook around the countersunk bolt - hole for compensating for the lack of strength caused by countersinking the hole on the under side to allow the bolt-head or nut to sink in said hole, so as not to come in contact with the animal's back and injure it, as would be the case if it projected below said shank.

Figure 1 is a front elevation of my improved gig saddle-tree. Fig. 2 is a top view. Fig. 3 is an under-side view of one-half of the tree. Fig. 4 is a sectional elevation of Fig. 3 on the line *x x*. Fig. 5 is a transverse section of Fig. 3 on the line *y y*. Fig. 6 is a plan view of the terret-nut. Fig. 7 is a side elevation of the terret-nut. Fig. 8 is a plan of the under side of the crupper-loop. Fig. 9 is a transverse section of Fig. 2 on the line *z z*. Fig. 10 is, partly, a side elevation and partly a sectional elevation of the check-rein hook, the section being taken on the line *v v* of Fig. 11. Fig. 11 is a top view of the shank of said hook. Fig. 12 is a plan view of the saddle. Fig. 13 is a section of Fig. 12 on the line *w w*. Fig. 14 is an elevation of a bolt and socket-nut used for bolting the check-rein hook, saddle, and tree together. Fig. 15 is an elevation of a bolt with a conical nut that may be used in substitution of the bolt and socket-nut shown in Fig. 14. Fig. 16 is a plan view of the middle leather which is placed between the saddle and top of the tree. Fig. 17 is a section of the saddle, middle leather, tree, check-rein hook, and the crupper-loop on the line *z z* and *w w*, showing the manner in which they are fitted to each other and connected together. Fig. 18 is a section like Fig. 17, showing the bolt and cone-nut used in place of the bolt and socket-nut in Fig. 14, also the hind bolt, not extending through the saddle as in Fig. 17; and Fig. 19 is a longitudinal elevation of the tree, showing the flaps secured on the under side of the flanges and the jockeys sewed down.

Similar letters of reference indicate corresponding parts.

Figs. 1 to 4, inclusive, show the improved

construction which I have devised to enable me to make the jockeys shorter than heretofore, while having the same or greater length and breadth of the bearing-plate of the frame; the said short jockeys being desirable to improve the appearance of the saddle.

Heretofore the flanges *a* and the parts *b*, which I call the bearings, have been extended to the end *c* of the plate, thereby extending the depressions between the walls *b* for the stiffeners and the tongues of the flaps, and, of necessity, requiring the jockeys *d*, Fig. 19, used to cover the said depressions and tongues, to be also extended as much.

Now, I propose to have these flanges and bearings terminate considerably short of the said ends *c*, as clearly shown in the drawing, for allowing me to use short jockeys; but, instead of narrowing the extensions *e* of the frame or plate of the tree down to the width of the webs *f* between the walls *b*, I make them as wide as the extensions of the flanges *a*, in order to get as broad and substantial bearings thereat as necessary to steady the saddle and keep it in proper place on the animal's back, and at the ends of the flanges I make the notches *g* to allow of sewing the jockeys to the flaps as near to the center as necessary to make a durable and handsome finish; thus the flat bearing portion of the tree is independent of the jockeys, and may be as long as desired to insure its sitting firm and square on the horse, no matter how short the flanges may be, and the flanges may be made short or long, as preferred. This arrangement also avoids the breaks which are usual at the ends of the jockeys when the flaps are secured under the flanges *a*, as represented in Fig. 19, which it is desirable to do under some circumstances. The holes represented in the flanges *a* and depressed parts of the tree are for nailing and riveting the tongue and flaps of the back-band to it. *h* represents the terret-nut, which I propose to provide with a lug or projection, *i*, on each side and in connection with the bottom plate *k* to enter corresponding notches, *l*, in the depressed parts *f* of the plate, when the nut is entered in the hole *m*, and the said plate *k* is adjusted between the ribs *n* to prevent the turning of the said terret-nuts when the terrets are screwed in or out. *o* represents the ribs, which I provide on the outer edges of the flanges *a*, which, to insure the forming of perfect and smooth edges in the casting, while allowing the said flanges to be thin enough between the said ribs and the bearings *b* to allow of punching the nail and rivet holes readily when they are not properly formed by the castings of the plates. *p* represents the front upright, and *p'* the back one on the crown of the tree. The one, *p*, is provided with a shoulder, *q*, near the upper end for the under side of the saddle to rest on, and a thinned portion, *r*, for extending up through the hole in the saddle for one of the bolts by which it is secured to the tree. This shoulder prevents the saddle-seat *S* from setting down too

far in front when screwed down. The thinner portion, extending up through the opening in the seat, holds firmly against moving about laterally on the tree. This front projection could be used without the shoulder depending on the back upright and edges of the seat resting on the jockeys to keep it from settling down two far; but, if so made, it would have to be too thin for sufficient strength to have the thinned portion extend up through the hole without having the hole too large, for, if thick enough to prevent bending, the hole in the saddle would have to be too large, for said hole must not be so large but that the head *t* of a socket-nut, *u*, or a bolt, *v*, will cover it and overlap the seat around the hole sufficiently to hold it in position, as shown in Fig. 17. I propose to use a second bolt, *u*, for securing the saddle, the tree, and the check-rein hook *x* together, the head of said bolt screwing into a countersink in the bottom of the shank *y* of said hook, flush with the surface, so as not to project and injure the horse, while the socket-nut drops into the hole *z* in the saddle and its head rests on the top of said saddle; but instead of this socket-nut and screw-bolt I may use a bolt, *v*, with a conical nut, *v'*, to fit into the countersink below, the bolt being inserted in the top; but in this case the nut will project slightly below the surface of *y* to allow of applying a wrench for turning it. Another screw-bolt, *y'*, will be used behind the upright *f'* for securing the saddle, and, being introduced from the bottom, it will either screw through the saddle, as shown in Fig. 17, or only part way through, as shown in Fig. 18. *a'*, Figs. 8, 17, and 18, is the detachable crupper-loop with its flat rectangular shank *b'*, in which, at the rear, is a square hole, *c'*, and at the front a round one, *d'*, by which it is secured firmly to the top of the tree-plate by the square projection *e'*, with a screw-threaded top, *f'*, on which is a nut, *g'*, screwing down firmly on said shank, and is prevented from turning by the bolt *y'* passing through the holes; but, in some cases, as in japanned seats, the round hole may be dispensed with, as the square hole and projection *e'* and a rib extending downward from the japanned seat may be depended on to hold the crupper-loop. From the rear end of the shank *b'* the loop *a'* rises up sufficiently to allow the rear cross-bar *h'* of the "middle leather" to pass under it, as clearly shown in Figs. 17 and 18; the said leather being arranged between the saddle and the top of the tree-plate, surrounding the uprights, connecting-bolts, and the shank *b'* of the crupper.

In order to compensate for the lack of strength in the shank *y* of the check-rein hook *x*, caused by countersinking the hole for the bolt *u* or *v*, I provide the conical elevation *i* on the upper side of said shank surrounding said hole, and I provide a corresponding conical-shaped hole at *k'* in the tree-plate to receive said projection when the said shank is secured to the plate, as shown in Figs. 17 and 18.

Having thus described my invention, I claim as new and desire to secure by Letters Patent—

1. The construction of the tree-plates with wide bearing parts *e* extending beyond the flanges and having notches *g*, substantially as specified.

2. The terret-nuts, having the projections *i* to fit in corresponding notches *l* in the tree-plates to hold the nuts against turning, all substantially as specified.

3. The flanges *a*, provided with ribs *o* on the outer edges for insuring perfect and smooth castings, and the remaining portions made thinner to allow of punching the holes readily, substantially as specified.

4. The front upright *p*, having the shoulder *q* for the saddle to rest on, and the thin por-

tion *r* extending up through the hole in the saddle, substantially as specified.

5. The detachable crupper-loop, having the square or angular hole *c'* in its shank fitted to the square or angular projections *e' f'* on the tree, and constructed to allow the "inside leather" to be placed under it, all substantially as specified.

6. The countersunk shank *y* of the check-hook, re-enforced by the conical projection *i*, substantially as specified.

The above specification of my invention signed by me this 5th day of December, 1871.

SAM. E. TOMPKINS.
